(57) **CLAIM**

The ornamental design for a water pitcher, as shown and described.

DESCRIPTION

FIG. 1 is a left rear perspective view of a water pitcher of the present invention;

FIG. 2 is a right side view thereof;

FIG. 3 is a left side view thereof;

FIG. 4 is a front view thereof;

FIG. 5 is a rear view thereof;

FIG. 6 is top view thereof; and,

FIG. 7 is a bottom view thereof.

The broken lines in the drawings are included for the purpose of illustration and form no part of the claimed design.

1 Claim, 4 Drawing Sheets
